DESIGN FOR A BATHTUB

Charles W. Carbeau, Ellwood City, Pa., assignor to Ellwood Company, Ellwood City, Pa., a corporation of Pennsylvania

Application February 17, 1936, Serial No. 61,198

Term of patent 14 years

To all whom it may concern:

Be it known that I, Charles W. Carbeau, citizen of the United States, residing at number 12, Second street, Elwood city, in the county of Lawrence and the State of Pennsylvania, have invented a new, original, and ornamental Design for a Bathtub, of which the following is a specification, reference being had to the accompanying drawing, forming a part thereof.

Figure 3 is an end elevation thereof, and
Fig. 4 is a transverse sectional view through
Fig. 2, on the line 4—4 of Fig. 2.

The dominant feature of the design resides in the angular downwardly extended flat rim of the tub.

I claim:

The ornamental design for a bathtub substantially as shown and described.

CHARLES W. CARBEAU.
